LOCK GUARD

Joseph Gangi, New York, N. Y.

Application April 17, 1950, Serial No. 156,469

7 Claims. (Cl. 292—346)

1

The present invention relates to improvements in lock guards and more particularly to guards for spring latches or locks, sometimes called night latches for doors.

Each of said night latches or locks comprises a lock proper carried by the door and a strike member or keeper attached to the corresponding door jamb. Said lock proper includes a spring-urged locking bolt with an inclined portion for engagement with said strike member or keeper as the door closes, to force the bolt back and then release it to engage said keeper. Such a latch or lock is ordinarily provided with bolt withdrawing means operable from the outside by a key and from the inside by a knob. Locks of this kind may be mounted at the inside of the door or in a mortice in the door, and the keepers may be modified correspondingly.

Such locks or latches have the disadvantage of being comparatively easy for unauthorized persons to unlock from the outside of the door. Withdrawal of the bolt from the keeper has often been effected by inserting a thin piece of metal, of Celluloid or of any other suitable material, between the locking edge of the door and the adjacent door jamb, and pressing the flexible member against the inclined end of the bolt. The bolt may be forced back and the door unlocked. Persons in general might find this operation difficult but many thieves have become so skillful that they perform such acts easily.

An important object of the invention is to provide novel and advantageous means to guard the lock so as to prevent unlocking thereof from the outside of the door without the use of a key.

Another object of the invention is to provide a novel and advantageous lock guard which is of comparatively simple and inexpensive construction, but is durable and highly efficient in use and can readily be installed in a usual door jamb.

Other objects, features and advantages will appear upon consideration of the following detailed description and of the drawings in which:

Fig. 1 is a sectional view illustrating one embodiment of the invention in which the lock guard is mounted on the strike member;

Fig. 2 is a front view of the locking means of Fig. 1;

Fig. 3 is a sectional view of the device of Fig. 2, taken along the line 3—3;

Fig. 4 is a section of the door jamb with the lock guard in its normal position while the door is open;

Fig. 5 is a view on a larger scale of the back

2

of a fragment of the strike member carrying the lock guard;

Fig. 6 is a section taken along the line 7—7 of Fig. 5;

Fig. 7 is a view similar to Fig. 5 but showing the lock guard as separate from the strike member;

Fig. 8 is a sectional view taken along the line 9—9 of Fig. 8;

Fig. 9 is a view of the face plate of the second embodiment of the invention; and

Fig. 10 is a view of a flat blank from which a part of the lock guard is formed.

Referring to the drawings, Fig. 1 illustrates 15 one edge of a door 15 in closed position with its edge close to the adjacent face of a door jamb 16 with a flange or projection 17 at its outer face serving as a stop to mark the outward or closing limit of movement of the door. Mounted on the 20 inside of the door is a lock proper 18, such as a spring lock or latch sometimes known as a night latch. As illustrated said lock or latch 18 is of a well known type and comprises a bolt 19 urged or biased outwardly by suitable means, such as 25 a compression spring (not shown). Said lock 18 may be secured to the door by screws 18a.

At its outer end, said bolt 19 is beveled to provide an inclined face 20, which, as the door closes, engages the inclined outer edge 21 of a bolt-receiving strike member or keeper 22 and is cammed back to enable it to pass said edge and move outwardly into a chamber 23 in a part of 30 said strike member which rests on the inner face of the door jamb 16. At the rear of said chamber 23 there is a wall 24 which is bent around the adjacent corner of the jamb and by the use of screw 35 25 the keeper is held firmly in position at this point. When the door 15 is to be opened, from inside the door, said bolt is drawn by turning a usual handle 26 at the rear of the lock 18, and when the door is to be opened from the outside a key is inserted in a part 28 of the lock at the outside surface of the door and turned in the proper direction. When the bolt is retracted it 40 may be secured in such position by shifting a button 29 in one direction as in the usual lock of this kind. Shifting the button 29 in the opposite direction will release the bolt.

As is customary the strike member or keeper 45 22 has a flat part or plate 30 extending across and countersunk in the face of the jamb 16. This plate 30 is also secured to the jamb 16 by two screws 31 in a well known manner. As here shown the plate 30 extends farther across the jamb than is usually the case, and substantially

to the flange 17 of the jamb 16. The reason for this is to enable a lock guard to be carried by said plate 30 and both the keeper and lock guard installed in one operation.

Near the flange 17, the plate 30 is provided with a rectangular opening 32 back of which is a recess 33 in the door jamb 16. In this opening is a guiding device 34, formed from a blank 34a of flat metal (Fig. 10), in the shape of a pointed arch which is pressed outwardly through said opening by means of a spring 35 wound around a pin 36 which is pressed against the inner edges of said device 34, the ends of said spring 35 being held in ears 37 projecting rearwardly from said plate 30. The device 34 is kept from moving out of said opening by means of projections or lugs 38 engaging said plate 30.

Secured to the inner side of the arched piece 34 is a plate 39 with its inner edge resting against plate 30 when the door is open. Said plate 39 may be fastened to member 34 in different ways but as here shown (Fig. 6) tongues 40 are punched up from the material of member 34 and secured in openings in plate 39.

At this point it may be noted that lugs 38 may be formed by forming notches 41 in blank 34a from which 34 is formed and then bending said lugs outwardly to project beyond the edges of the blank end of the finished member 34.

In Figs. 7, 8 and 9, the lock guard is illustrated as having a face plate 30a separate from plate 30 of the keeper. Otherwise the lock guard is the same as illustrated in Figs. 1 through 6.

The corner of the door edge adjacent to the lock guard when the door is closed is preferably protected by an angle piece 42 countersunk in the material of the door and held in position by one or more screws 43. This angle piece or protector 42 serves to prevent the corner of the door from being chipped away by implements which burglars may attempt to insert between the door and the jamb for the purpose of forcing back the bolt 19 to unlocking position.

The plate 39 may be said to have a floating support by means of member 34. The positions of the parts of the lock guard when the door is open are shown in Fig. 4. The member 34 is in its outward position determined by engagement of lugs 38 with the inner face of plate 30. The plate 39 is inclined with an edge 44 close to the plate 30 and the opposite edge 45 spaced away from the plate, the edge 44 being toward the keeper which cooperates with bolt 19.

As the door is closed, the protector 42 engages the plate 39 and swings it back toward the plate 30. Simultaneously the member 34 is forced inwardly through the opening 32, against the action of the spring 35. When the parts of the lock guard are thus located, it would be impossible to insert a bolt retracting device without breaking the lock guard, and that would be practically impossible.

Suppose a thin strip of metal or Celluloid were worked around the edge of the door 15 and between the same and plate 30. Then it would ordinarily engage the edge of plate 39 and be blocked, the plate being supported by the opposite side of member 34 engaging the opposite side of opening 32. If the end of the strip got between the plate 39 and plate 30, it would be blocked by member 34.

The device of the present invention provides an inexpensive and effective lock guard.

It should be understood that various changes can be made and that certain features may be used without others, without departing from the true scope and spirit of the invention.

5. What is claimed is:

1. A lock guard comprising a supporting face plate having an opening, a blocking plate at the front of said face plate, and means for yieldably holding said blocking plate in inclined position in front of said face plate with one edge resting against the face plate, including a device attached to said blocking plate for swinging movement through said face plate and spring means at the rear of said face plate to hold said device in advanced position.

2. A lock guard according to claim 1 wherein said opening in said face plate is rectangular, said device in a direction longitudinal of said blocking plate fits in said opening and there are cooperating parts of said face plate and device to prevent movement of said device completely out of said opening.

3. A lock guard according to claim 2 wherein said spring means includes a spring-supported pin on which said device is balanced.

4. A lock guard device comprising a face plate having a lock guard, said face plate having a rectangular transverse opening, a blocking plate over said opening, and means extending through said opening for yieldably holding said blocking plate in inclined position with an edge close to said face plate, comprising a member with an arched outer surface to one side of which said blocking plate is secured, means for limiting the outward movement of said member and spring means for urging said member outwardly.

5. A lock guard device according to claim 4 wherein said means for limiting the outward movement of said member consists of lugs projecting from said member in position to engage the rear face of said face plate.

6. A lock guard device according to claim 4, wherein said spring means comprises a pin to engage said member at opposite edges thereof, a spring coiled around said pin and having its ends extending to the ends of the face plate opening, and means at the ends of said opening for holding said ends of the spring.

7. A lock guard comprising a face plate with a rectangular opening therethrough and rearwardly projecting ears, a member in the form of a pointed arch projecting through said opening from the rear of the plate and having lugs at its corners to engage said face plate and limit the forward movement of said member, spring means at the rear of said face plate and connected to said ears urging said member to its forward position, and a blocking plate secured to said arch member at one side thereof.
